UNITED STATES PATENT OFFICE.

ADOLPH HELMUS AND ISIDOR DREYFUSS, OF NEW YORK, N. Y.

DESIGN FOR A REEL.

SPECIFICATION forming part of Design No. 15,146, dated July 15, 1884.

Application filed March 7, 1884. Term of patent 3½ years.

To all whom it may concern.

Be it known that we, ADOLPH HELMUS and ISIDOR DREYFUSS, citizens of the United States, residing at New York, in the county and State of New York, have invented and produced a new and original Design for Reels, of which the following is a specification, reference being had to the accompanying drawing, forming part thereof.

Our design consists in a new and original shape or configuration and ornamentation for a reel. The general form of the reel is rectangular, as shown in the drawing. In this skeleton rectangular outline the ends *a* project beyond the ends *c*, presenting the appearance

approximately of double-cross shape at the four corners *c* of the reel. Ornamental disks *f*, centrally displayed at the double-cross-shaped ends, add very naturally to the attractiveness and effectiveness of the design. 20

What we claim is—

The design for a reel, consisting of the rectangular skeleton reel shown, having ends *c*, sides *a*, cross-rods *e*, and ornamental disks *f*, as set forth.

ADOLPH HELMUS.
ISIDOR DREYFUSS.
